UNITED STATES PATENT OFFICE.

HUGH WALLACE, OF DAYTON, OHIO, ASSIGNOR TO GENERAL MOTORS RESEARCH CORPORATION, OF DAYTON, OHIO, A CORPORATION OF DELAWARE.

FUEL-SUPPLY DEVICE.

Application filed August 3, 1925. Serial No. 47,876.

This invention relates to a fuel supply device for internal combustion engines, and more particularly to the type in which the fuel is lifted from a main supply tank and delivered to an auxiliary reservoir, from where it is delivered by gravity to the carburetor of the engine.

It is among the objects of the present invention to provide a fuel supply device particularly adapted for use in connection with motor-vehicle engines, and so constructed and arranged as to be capable of being installed in vehicles having limited space.

Another object is to construct and arrange the various elements of the device so as to reduce the number of connections acting as liquid fuel conduits, whereby the chances of fuel leaks are substantially reduced.

Further objects and advantages of the present invention will be apparent from the following description, reference being had to the accompanying drawings, wherein a preferred form of embodiment of the present invention is clearly shown.

In the drawings:

Fig. 1 is a sectional view of the auxiliary reservoir, taken along the line 1—1 of Fig. 2;

Fig. 2 is a cross section taken through line 2—2 of Fig. 1;

Fig. 3 is an inverted plan of the auxiliary reservoir;

Fig. 4 is a detail section taken on line 4—4 of Fig. 2, and illustrates the fuel passages and inlet and outlet check valves;

Fig. 5 shows the fuel supply device installation on a four-cylinder, internal combustion engine; and

Fig. 6 is a detail, longitudinal section of the pulsator and portions of the engine.

Referring to the drawings, and more particularly to Fig. 5, there is shown an internal combustion engine 20 provided with a manifold 21 to which is secured a carburetor 22. The carburetor 22 has a float bowl 23 having an inlet port 24 provided with connections for attaching the fuel pipe 25.

The numeral 26 indicates the auxiliary fuel reservoir secured on the body of the motor vehicle in any suitable manner and at a higher level than the carburetor. This auxiliary reservoir comprises a base 27 provided with a ring 28 which may be formed integral with the base 27 on the upper surface thereof and near its periphery; or, may, as shown in the drawing, be secured to said

base by means of screws 29—a gasket 30 being positioned between the base and ring to prevent leakage at this point. A casing 31 forms the reservoir, fitting closely about the ring 28 and being welded thereto to prevent leakage. In the upper portion of the casing 31 is an opening 32 over which a vent cap 33 is secured. Plate 34 is provided in the opening 32, having vent holes 35 and a central opening for receiving a stem. Pipe 36, which extends into the cap 33, provides an air vent for said cap.

A housing 37 having a flange portion 38 is secured to the bottom surface of the plate 27 by means of screws 39. This housing 37 includes a depending portion hollowed out to form the chamber 40, in which there is positioned a screen 41 held in position in this chamber by means of a plug 42 which is screw-threaded into the lower end of the depending portion of housing 37. A gasket 43 is provided at the joint between the portion 37 and the plug 42, to prevent fuel leakage at this point. A fuel inlet port 44 is formed in the wall of the depending portion of housing 37. A lug 45 is formed integral in the housing and is provided with a passage 46 which communicates with a channel 47 formed in the housing block, the opposite end of the passage 46 being screw-threaded as at 48 to receive the connection for the pipe 49 leading to the pulsator.

The interior of the screen element 41, located in the chamber 40, is in communication with a passage 50 formed in an enlarged portion of the base 27 extending up into the casing 31. The passage 50 is in communication with a reduced portion 51 in axial alignment with said passage 50, thus forming a shoulder 52 which acts as a seat for the valve element 53, to be described hereinafter. Passage 51 has a communicating passage 54 in which there is provided a check valve 55, which may be termed the "inlet check valve." This valve is held against its seat 56, formed in the passage 54, by means of a spring 57, said spring being interposed between the check valve 55 and a collar 58 held in position between the base 27 and the gasket 59; which in turn is provided between the cap 27 and housing 37. The collar 58 is provided with an upwardly-extending sleeve 60 which has transverse passages 61. This sleeve 60 is positioned in the passage 54 for the purpose of limiting the downward travel of the in-

take valve 55 when it moves from its seat 56, by means of suction.

The passage 54 is in communication with the passage 47 formed in the housing 37. 5 This passage 47 is connected with an opening 62 formed in the base 27, which in turn communicates with the interior of a tube 63 secured in an opening in the ring 28. A cover 64 is provided in the upper end of this 10 tube. A pipe 65 is secured in the passage 46, this pipe extending up into the tube 63 so that its upper end is adjacent the cover 64. The opposite end of the pipe is, as has been mentioned, secured in the passage 46 of the 15 lug 45 and communicates with the port 48 with which pipe 49 is connected.

In the Fig. 3 it may be clearly seen in dotted lines that the passage 47 is of Y formation, the base thereof being that portion which communicates with the interior 20 of the tube 63. The upper or left-hand branch of the Y passage 47 communicates with the passage 54 in which inlet check valve 55 is located. The lower or right-hand branch of the Y-formed passage is 25 designated by the numeral 66. This branch communicates with the passage 67 formed in the seat for the outlet valve 68, which is located in the valve chamber 69 formed in 30 the base portion 27. A sleeve 70, provided in this housing 69, is secured in the upwardly-extending portion of the base 27 in any suitable manner. A spring 71 is interposed between a shoulder formed in the 35 outlet passage 72 and tends to maintain the valve 68 in engagement with its seat 67. In the Fig. 4 it may be seen that the discharge end of the outlet passage 72 is located a substantial distance above the base 27 which 40 forms the bottom of the tank, thus causing passages 66 and 47, together with a portion of the tube 63, to form a chamber in which fluid is trapped for maintaining the device primed during non-operation. A port 73 is 45 formed in the base 27, this port being an outlet for the reservoir 26, and to which the pipe 74 leading to the carburetor is connected.

The valve 53, mentioned heretofore, is carried on a stem 80 which axially extends up to the passage 51 through a passage 81 formed in the ceiling of the passage 51 and providing communication between the passage 51 and the inside of casing 31. The upper peripheral edge of this passage 81 forms a 55 valve seat for the valve 82, which is connected with the stem 83, the opposite end of which extends through a guide hole formed in the plate 34. A float element 84 has a 60 tubing 85 passing therethrough, this tubing in turn having the stem 83 extending through it. The lower end of the tubing 85 has a spring 86 secured thereto, the opposite end of the spring being secured to a pin 87 65 carried by the stem 83. This spring 86

forms a flexible connection between the float element 84 and the stem 83. Pipe 90 connects the fuel inlet port 44 of the screened chamber 40, with the main fuel tank 91. The stem 83 is provided with a ball-shaped 70 end, as shown in Fig. 1, which is loosely secured in a socket formed on the end of valve 82. This structure provides a swivel connection between the two-way valve including valves 53 and 82 carried by stem 80 and 75 the stem 83. The stem 83 being of lesser transverse dimension than the aligned aperture formed in the plate 34 and the connection between the stem 83 being loose it naturally follows that the stem 83 will not 80 become cocked and thereby stick when the movement of the float 84 being lifted by the fuel in the tank 31, tends to raise the valve 82 from its seat and lift the valve 53 against 85 its seat.

In Fig. 6, a pulsator is shown comprising a cylinder 100 having flanges 101, by means of which the pulsator is secured to the engine crankcase 102. An extension 103 of the cylinder 100 extends into an opening 104 of the crankcase, said extension being provided with longitudinal slots 105 for receiving a pin 106 which also extends through slots 107 formed in the piston 108. The other end of the piston 108 is provided with a plug cap 109. A coil spring 110 is secured to this cap 109, the opposite end of said spring being anchored to the pin 106. The end of the piston 108 opposite the plug 109 is provided with a cam follower 111. This cam follower is held in engagement with the engine-driven cam 112, due to the action of the spring 110, which will tend to draw the pin 106 to the left, as regards Fig. 6, holding it in engagement with the inner end of the slot 105 in the cylinder extension 103, while drawing the piston 108 to the right, so that the follower 111 will engage with the cam 112. In this position, the pin 106 is also in engagement with the left end of the slots 107 formed in opposite sides of the piston wall. Port 113 is formed in the outer end of cylinder 100, said port receiving one end of the pipe 49, the other end of which is connected with the port 48 of the auxiliary reservoir. 115

When the engine is operating, the cam 112 will force the piston 108 to the left, as regards Fig. 6, compressing the air within the space between the piston and the cylinder head, thus providing compression through the pipe 49 and in the stand pipe 65; and, therefore, in the tube 63 and the passage 47, which passage may be termed the "fuel relay chamber". When the cam 112 of the engine moves toward the position as shown in Fig. 6, the spring 110 will move the piston in the opposite direction, or to the right, as regards Fig. 6, thus rarefying the air in the fuel relay chamber 47. As the 120

air in the fuel relay chamber 47 is rarefied, the inlet check valve 55 will be moved away from its seat against the edge of the spring 57, thus creating suction in the chamber 47. 5 Fuel will be lifted from the tank 91 through the pipe 90, thence it will enter into the chamber 40, pass through the screen 41 and enter into the passage 50. Assuming that the level of the fuel in the casing 31 is at 10 a low point, the float 84 will be in its low position, thus causing the spring 86 to release its pull on the pin 87 and thereby permit the stem 83 to push the valve 82 against its seat in passage 81, shutting off communication between the passage 51 and the interior of the casing 31. In this position the valve 53 will be off its seat on shoulder 52. Thus the fuel may flow from the passage 50 15 past the valve 53 into the passage 51 and thence through the passage 54, past the inlet check valve 55, through transverse passages 61 into the interior of the sleeve 60 and into the fuel relay chamber or passage 47. Upon 20 the reverse stroke, or pressure stroke, of the piston 108, the fuel in this passage or fuel relay chamber 47 will be forced out through passage 66, lifting the valve 68, thence passing into the chamber 69 through passage 72 into the interior of the casing 31. From 25 this point the liquid fuel will flow by gravity through the port 73, pipe 74 into the carburetor bowl 23 through inlet port 24.

When the level of the fuel in the casing 31 has reached a proper height, so that the 30 float element 84 will be raised sufficiently to tension the spring 86 and cause it to exert a pull on the pin 87, the stem 83 will be moved sufficiently upward to draw the valve 53 against its seat on shoulder 52 and move the 35 valve 82 from its seat, thus positively closing communication between the passage 50 and passage 54, and opening communication between the interior of the casing 31 and passage 54. Under these conditions, suction and pressure strokes of the pulsator will 40 tend to draw fuel from the interior of the casing 31, through passage 81, into the passage 54 and down into the fuel relay chamber, and then force said fuel up through its 45 normal path, past the outlet valve 68 back into the casing 31. From this it may be seen that while the float element 84 is maintained above a proper high level, fuel will 50 be circulated from the interior of casing 31 55 around the described paths, back into said casing, thus maintaining a supply of fuel which may, by gravity, flow to the carburetor,—this flow being absolutely controlled by the fuel-flow-controlling element in the carburetor bowl. It will, of course, be seen 60 that as soon as the float reaches a proper low level, the valves 82 and 53 will again be moved so that fuel may flow from the main tank 91 into the relay chamber and

properly be delivered to the interior of the 65 casing 31.

By this arrangement the connections through which liquid fuel must pass are substantially reduced, they being only four in number. Thus the liability of fuel leaks 70 is substantially reduced. The pulsator may be located in any suitable position on the engine, inasmuch as a flexible tubing is the only connection between it and the auxiliary reservoir,—this tubing being the conductor 75 of air only. The tube and stand pipe 63 and 65, respectively, are provided so that they will extend beyond the high level of the fuel, thereby eliminating the possibility of liquid fuel being drawn down into the pulsator. 80

While the form of embodiment of the present invention as herein disclosed, constitutes a preferred form, it is to be understood that other forms might be adopted, all coming within the scope of the claims which 85 follow.

What is claimed is as follows:

1. A fuel supply device, comprising in combination, a tank having an open end provided with an inwardly extending flange; a pulsator tube attached to the flange and extending within the tank, the inner end of said tube being closed, the end of the tube attached to the flange being open and in communication with an aperture in said flange; a base secured to the flange of the tank, said base having valved inlet and outlet passages; an intermediate passage in the base providing communication between the tube and the inlet and outlet passages when the base is attached to the tank; and a pressure pipe attached to the base and extending into the tube when said base is attached to the tank. 95

2. A fuel supply device comprising in combination, a tank having one open end; a base attached to the open end of said tank forming a bottom therefor; valved inlet and outlet passages in said base; an intermediate passage in said base communicating with the inlet and outlet passages; a tube within the tank having a closed end adjacent the closed top end of the tank, the open end of said tube communicating with the intermediate passage; and a pressure pipe extending into the tube so that its one end is adjacent the closed end thereof, the other end of said pipe extending through and being attached to the base. 110

3. A fuel supply device comprising in combination, a tank having one closed end; a base attached to the open end of said tank and providing a bottom therefor, said base having a housing portion extending into the tank, the housing portion being provided with inlet and outlet passages; check valves in said passages; a tube extending within the tank and having a closed end adjacent 120

- the closed end of the tank and an open end communicating with an aperture in the base; a housing member secured to said base, said member having a passage communicating with one of the passages in the base and a second passage providing communication between both passages in the base and the aperture which communicates with the tube; and a pipe extending through and secured to the housing member, said pipe extending into the tube and terminating adjacent the closed end thereof when the said member is attached to the base.
4. A fuel supply device comprising in combination, a tank having one closed end; a base attached to the open end of said tank and providing a bottom therefor, said base having a housing portion extending into the tank, the housing portion being provided with inlet and outlet passages, the outlet passage extending upwardly into the tank so

as to discharge into the said tank a substantial distance above the base of the tank; check valves in said passages; a tube extending within the tank and having a closed end adjacent the closed end of the tank and an open end communicating with an aperture in the base; a housing member secured to said base, said member having a passage communicating with one of the passages in the base and a second passage providing communication between both passages in the base and the aperture which communicates with the tube; and a pipe extending through and secured to the housing member, said pipe extending into the tube and terminating adjacent the closed end thereof when the said member is attached to the base.

In testimony whereof I hereto affix my signature.

HUGH WALLACE.
